CRUSHED-FUEL STOKER HAVING MEANS
FOR EQUALIZING THE DISTRIBUTION OF
FUEL UPWARDLY IN THE RETORTCornelius Quist, Grand Rapids, Mich., assignor to
Holland Furnace Company, Holland, Mich., a
corporation of Delaware

Application October 17, 1945, Serial No. 622,838

4 Claims. (Cl. 110—45)

1

This invention relates to a stoker for furnaces and other heating units and more particularly to an underfeed stoker in which the crushed coal or other solid fuel of suitable fineness is forced upwardly through the retort with a uniform upward filling of the upper portion of the retort.

In stokers as heretofore known the crushed coal or similar fuel, when being forced upwardly through the retort, under the action of a screw or other means for forcing the fuel from a hopper through the fuel tube, has had a tendency to climb up one side of the retort neck due to the rotation of the coal screw. This action causes the coal to move along one side of the retort more than the other with the result that the coal rises unevenly in the retort. In the present invention I have provided means for overcoming this difficulty and causing a uniform and even upward continuous filling of the upper portion of the retort. My present invention equalizes the distribution of the coal so that in the upper portion of the retort all of the coal is moved vertically upward in parallel layers. Segregation of the larger particles of coal is prevented and the coal is kept thoroughly mixed.

Among the objects of my invention are to provide a novel and improved stoker; to provide a stoker in which coal segregation is eliminated, and in which the coal rises evenly in the retort; to provide a novel form of retort cooperating with the feed screw of the stoker to attain such a result; more particularly to provide a novel form and arrangement of retort and rib for equalizing the distribution of the coal upwardly in the retort; to provide means for overcoming the disadvantages and accomplishing the advantages hereinbefore referred to.

Other objects and advantages will appear from the following detailed description, taken in connection with the accompanying drawings, wherein:

Fig. 1 is a side elevation of a stoker embodying my invention.

Fig. 2 is a longitudinal vertical central section through the retort and adjacent section of the coal tube and associated parts.

Fig. 3 is a top plan view of the retort and adjacent section of the coal tube shown in Fig. 2.

Fig. 4 is a fragmentary longitudinal enlarged section on the line 4—4 of Fig. 2.

Fig. 5 is a section on the line 5—5 of Fig. 2.

While my invention resides in the combination, construction and arrangement of parts illustrated in the accompanying drawings, I have shown therein for illustrative purposes only, a preferred

embodiment, and wish it understood that the same is susceptible of modification and change without departing from the spirit and scope of the appended claims.

While I refer herein to crushed coal as the preferred fuel, I wish this term to include any other crushed or sufficiently fine and solid fuel that may be adapted for use in the stoker shown and described herein.

My improved stoker comprises generally a hopper 1, a blower 2, a coal tube 3 and a retort having a bowl 4. Rotatably mounted and extending longitudinally in the coal tube 3 is a screw conveyor 5 for conveying the crushed coal longitudinally along this tube from the hopper to the retort. A conduit 6 leads from the blower to a sheet metal casing 7 and from said casing air passes to the upper portion of the retort. The conduit 6 is preferably placed to one side of the coal tube as indicated in Fig. 3. The sheet metal casing 7 is positioned around the coal tube 3 and has its side walls spaced a sufficient distance from the sides of the coal tube to provide an air passageway on each side of the tube for conducting the air along the coal tube and introducing it into the retort on both sides of the coal tube. Extending longitudinally along the top of the coal tube within the casing 7, is a rib 8 whose upper edge is spaced a distance below the top of the casing to permit passage of air from passageway 8' to passageway 8'' as well as longitudinally of the coal tube, which air may also pass laterally through any space that may be provided between the bottom of the coal tube and the bottom of the casing 7 if desired. These air spaces 8' and 8'' (Fig. 3) jointly conduct the air into space 9 in the hollow sectional casing 10, hereinafter referred to as tuyères, positioned around the retort 4 (see Fig. 2) and extending a desired distance thereabove to provide the upper portion 11 of the retort. Suitably formed in this upper portion of the retort are openings 12 for conducting air under pressure into the firebed in the top part of the retort. Should it be desired that the firebed extend somewhat around the outside of the retort top additional openings 13 may be provided in the outer tuyère walls 10 for directing air under pressure into that portion of the firebed.

A suitable door 14 is provided in the top of the hopper 1 and provided with suitable hinges (not shown) and a securing latch 15 to hold the lid or cover closed in an air tight condition if desired. A suitable motor 16 is provided adjacent the hopper for rotating the fan blades of the blower

2. Gearing 35 between the motor shaft and the feed screw provides a drive for the screw. As stated, the air conduit from the blower is outside of the coal tube. A suitable door 17 is provided for enabling access to the chamber within which the blower and motor are mounted.

In screw conveyor stokers known prior to my invention there has been an undesirable tendency of the feed screw to feed the coal excessively at one side of the retort thus giving an uneven distribution of the coal upwardly in the retort. This greatly lessens the efficiency of the firebed and prevents the desired results of the stoker. In these old stokers heretofore known, the coal while being forced forwardly by the screw conveyor, has a tendency to climb up one side of the retort neck due to the rotation of the feed screw.

I have overcome the above-mentioned difficulties in part by placing a rib 18 in the retort as shown in Figs. 2-5, which rib as shown extends downwardly at an angle along one side of the throat 19 of the retort and approximately along the juncture of the throat wall and the wall of the retort bowl. This rib, as will be understood in Figs. 4 and 5, is gradually curved on its forward and rear sides to merge into the retort wall 4 and the wall 19 of the throat, respectively, as shown at 20 and 21 in Fig. 4. As seen in Fig. 5, the inner edge of the rib 18 extends inwardly a substantial distance with relation to the circumference or wall 23 of the coal tube, and the rib extends from the bottom 24 of the retort throat 19 to the upper side of the throat 19. A neck portion 22 of the retort is preferably flared as shown at 23 to form a gradually enlarging entrance into the retort bowl from the coal tube.

With a feed screw as shown, rotating in a clockwise direction as viewed in Fig. 5, the front end of the screw acts to push the coal forwardly into the retort but also in a predominantly upward direction on the left hand side only of the axis of the screw. By placing rib 18 adjacent the juncture of the neck with the retort, the movement of coal from the screw is diverted in such a way that substantially equal amounts move towards both sides of the retort and the coal is lifted by the action of the screw conveyor and rib into the narrow angular channel which forms the retort throat. In this way the coal is not only evenly distributed in the retort, but also enters the retort with a minimum of segregation. The neck and throat being flared as shown in the drawings, this provides room for the coal to rise and be distributed as referred to above, instead of packing tightly. The rib holds back the coal so that it may rise on the screw to the top of the screw and then be ejected upwardly. The coal is thus lifted up into the throat rather than pushed directly from the coal tube to rise too fast up the back side of the retort. This action of the coal in the throat continues until the coal is about level with the throat and then part of the coal lifts up through the throat and part is pushed over the heel 24 of the retort so that the coal rises uniformly in parallel strata to evenly distribute the coal in the retort and to rise to the top thereof with a crowned surface. This equalizes the distribution of the coal and prevents segregation of the larger particles from the smaller particles which remain thoroughly mixed.

Formed centrally of the upper side of the coal tube 3 and spaced longitudinally within the casting 1 are two hollow members 25 and 26, the adjacent top side of the coal tube having a pair of slots 27 and 28 leading from the hollow in-

terior of these members to the interior of the coal tube. Member 25 is formed in each of its lateral sides with openings 29 and 30 whereby air under pressure may be forced from the interior of the hollow casing 1 through slot 27 to the interior of the coal tube to create a pressure of air in the coal tube toward the retort. This tends to drive any smoke or gases of combustion coming from the retort in the opposite direction, that is, away from the hopper and back toward the retort, due to the fact that coal entering the coal tube from the hopper is tightly packed at the spike trap. Screwed into the top of member 26 is a pipe 31 leading to the interior of the hollow member 26 and communicating with the slot 28, the other end of the pipe generally communicating with the interior of the furnace or connected in any manner with the flue so as to take advantage of its suction, through pipe 31, which will in turn create a focal discharge point at slot 28 for smoke or gases of combustion from the interior of the coal tube and lead the same into the furnace or flue to eventually pass out through the flue. The sides of the member 26 will preferably be closed by plugs 32 to prevent entry of air from the interior of the casing 1 to the interior of the pipe 31 so that the only passage into pipe 31 will be through slot 28 and through the hollow interior of member 26. This construction forms an efficient means for preventing the passage of smoke or gases of combustion backwardly from the retort to the hopper.

I claim:

35. 1. A stoker comprising a hopper, a fuel tube, a screw conveyer in the tube, a retort having a heel wall, an outwardly flaring neck having a throat between the tube and the retort, and a rib positioned on the wall of the retort adjacent the throat and near the upwardly movable side of the screw, and extending upwardly along one side of the neck, said rib being formed with a gradual curve on its two sides merging into the respective walls of the neck and the retort and at its ends merging into the throat and heel walls respectively, and having its edge extending inwardly and gradually increasing from bottom to top and extending inwardly a substantial distance at the top, the screw when the neck is full of fuel lifting up part of the fuel into the throat at the rib side and pushing part of it along the bottom of the retort so that the fuel rises to the top of the retort with a crowned surface in uniform upward distribution.
40. 2. A stoker comprising a tube adapted to have fuel such as crushed coal forced therethrough, a rotatable screw for forcing said fuel through the tube, a retort at the outlet end of the tube having a bowl and having a neck increasing in size from the diameter of the tube to the lower interior of the bowl to form a throat at the juncture of the neck and bowl, and means in the retort adjacent the throat thereof for obstructing free passage of the fuel into the retort bowl comprising a rib in the retort beginning at the upper side of the throat and extending downwardly at an angle and approximately along one side of the throat at the juncture of the neck and the wall of the retort bowl, said rib being gradually curved on its forward and rear sides to merge into the wall of the retort bowl and the wall of the neck respectively, and having its edge extending inwardly and gradually increasing from bottom to top and extending inwardly a substantial distance at the top and stretching from the
45. 3. A stoker comprising a tube adapted to have fuel such as crushed coal forced therethrough, a rotatable screw for forcing said fuel through the tube, a retort at the outlet end of the tube having a bowl and having a neck increasing in size from the diameter of the tube to the lower interior of the bowl to form a throat at the juncture of the neck and bowl, and means in the retort adjacent the throat thereof for obstructing free passage of the fuel into the retort bowl comprising a rib in the retort beginning at the upper side of the throat and extending downwardly at an angle and approximately along one side of the throat at the juncture of the neck and the wall of the retort bowl, said rib being gradually curved on its forward and rear sides to merge into the wall of the retort bowl and the wall of the neck respectively, and having its edge extending inwardly and gradually increasing from bottom to top and extending inwardly a substantial distance at the top and stretching from the
50. 4. A stoker comprising a tube adapted to have fuel such as crushed coal forced therethrough, a rotatable screw for forcing said fuel through the tube, a retort at the outlet end of the tube having a bowl and having a neck increasing in size from the diameter of the tube to the lower interior of the bowl to form a throat at the juncture of the neck and bowl, and means in the retort adjacent the throat thereof for obstructing free passage of the fuel into the retort bowl comprising a rib in the retort beginning at the upper side of the throat and extending downwardly at an angle and approximately along one side of the throat at the juncture of the neck and the wall of the retort bowl, said rib being gradually curved on its forward and rear sides to merge into the wall of the retort bowl and the wall of the neck respectively, and having its edge extending inwardly and gradually increasing from bottom to top and extending inwardly a substantial distance at the top and stretching from the
55. 5. A stoker comprising a tube adapted to have fuel such as crushed coal forced therethrough, a rotatable screw for forcing said fuel through the tube, a retort at the outlet end of the tube having a bowl and having a neck increasing in size from the diameter of the tube to the lower interior of the bowl to form a throat at the juncture of the neck and bowl, and means in the retort adjacent the throat thereof for obstructing free passage of the fuel into the retort bowl comprising a rib in the retort beginning at the upper side of the throat and extending downwardly at an angle and approximately along one side of the throat at the juncture of the neck and the wall of the retort bowl, said rib being gradually curved on its forward and rear sides to merge into the wall of the retort bowl and the wall of the neck respectively, and having its edge extending inwardly and gradually increasing from bottom to top and extending inwardly a substantial distance at the top and stretching from the
60. 6. A stoker comprising a tube adapted to have fuel such as crushed coal forced therethrough, a rotatable screw for forcing said fuel through the tube, a retort at the outlet end of the tube having a bowl and having a neck increasing in size from the diameter of the tube to the lower interior of the bowl to form a throat at the juncture of the neck and bowl, and means in the retort adjacent the throat thereof for obstructing free passage of the fuel into the retort bowl comprising a rib in the retort beginning at the upper side of the throat and extending downwardly at an angle and approximately along one side of the throat at the juncture of the neck and the wall of the retort bowl, said rib being gradually curved on its forward and rear sides to merge into the wall of the retort bowl and the wall of the neck respectively, and having its edge extending inwardly and gradually increasing from bottom to top and extending inwardly a substantial distance at the top and stretching from the
65. 7. A stoker comprising a tube adapted to have fuel such as crushed coal forced therethrough, a rotatable screw for forcing said fuel through the tube, a retort at the outlet end of the tube having a bowl and having a neck increasing in size from the diameter of the tube to the lower interior of the bowl to form a throat at the juncture of the neck and bowl, and means in the retort adjacent the throat thereof for obstructing free passage of the fuel into the retort bowl comprising a rib in the retort beginning at the upper side of the throat and extending downwardly at an angle and approximately along one side of the throat at the juncture of the neck and the wall of the retort bowl, said rib being gradually curved on its forward and rear sides to merge into the wall of the retort bowl and the wall of the neck respectively, and having its edge extending inwardly and gradually increasing from bottom to top and extending inwardly a substantial distance at the top and stretching from the
70. 8. A stoker comprising a tube adapted to have fuel such as crushed coal forced therethrough, a rotatable screw for forcing said fuel through the tube, a retort at the outlet end of the tube having a bowl and having a neck increasing in size from the diameter of the tube to the lower interior of the bowl to form a throat at the juncture of the neck and bowl, and means in the retort adjacent the throat thereof for obstructing free passage of the fuel into the retort bowl comprising a rib in the retort beginning at the upper side of the throat and extending downwardly at an angle and approximately along one side of the throat at the juncture of the neck and the wall of the retort bowl, said rib being gradually curved on its forward and rear sides to merge into the wall of the retort bowl and the wall of the neck respectively, and having its edge extending inwardly and gradually increasing from bottom to top and extending inwardly a substantial distance at the top and stretching from the
75. 9. A stoker comprising a tube adapted to have fuel such as crushed coal forced therethrough, a rotatable screw for forcing said fuel through the tube, a retort at the outlet end of the tube having a bowl and having a neck increasing in size from the diameter of the tube to the lower interior of the bowl to form a throat at the juncture of the neck and bowl, and means in the retort adjacent the throat thereof for obstructing free passage of the fuel into the retort bowl comprising a rib in the retort beginning at the upper side of the throat and extending downwardly at an angle and approximately along one side of the throat at the juncture of the neck and the wall of the retort bowl, said rib being gradually curved on its forward and rear sides to merge into the wall of the retort bowl and the wall of the neck respectively, and having its edge extending inwardly and gradually increasing from bottom to top and extending inwardly a substantial distance at the top and stretching from the

bottom of the retort bowl to the upper side of the throat.

3. A stoker comprising a tube adapted to have fuel such as crushed coal forced therethrough, a rotatable screw for forcing said fuel through the tube, a retort at the outlet end of the tube having a bowl and having a neck increasing in size from the diameter of the tube to the lower interior of the bowl to form a throat at the juncture of the neck and bowl, and means in the retort adjacent the throat thereof for obstructing free passage of the fuel into the retort bowl comprising a rib extending from a point near the bottom of the throat upwardly along the side along which the screw surface rises and merging into the wall of the throat above the top of the screw, said rib being gradually curved on its forward and rear sides to merge into the retort wall and the wall of the throat respectively, and having its edge extending inwardly and gradually increasing from bottom to top and extending inwardly a substantial distance at the top.

4. A stoker comprising a fuel tube, a rotatable screw in the tube for forcing fuel such as crushed coal therethrough, a retort at the outlet end of the tube and having a bowl, a neck gradually enlarging in size from the inside diameter of the tube to the lower interior of the bowl to form a throat at the juncture of the neck and bowl, and means in the retort adjacent said throat for equalizing the distribution of fuel upwardly in

the retort comprising a rib extending from the bottom of the throat diagonally upwardly and rearwardly of the throat to a point higher than and to one side of the screw, said rib having its longitudinal free-edge concave, said free-edge extending inwardly and gradually increasing from bottom to top and extending inwardly a substantial distance at the top and being gradually curved on its forward and rear sides to merge into the wall of the retort bowl and the wall of the neck respectively.
